ROLL PAPER CHUCK

Walter C. George, St. Louis, Mo., assignor to
 Robert Gaylord, Incorporated, St. Louis, Mo.,
 a corporation of Missouri

Application December 6, 1934, Serial No. 756,370

3 Claims. (Cl. 242—72)

My invention relates to a roll paper chuck and particularly to a chuck adapted to carry large and heavy rolls such, for example, as are used to supply to a corrugating machine the component sheets for forming corrugated fiberboard. It has been usual heretofore to support such rolls on a shaft having, adjacent its ends, a pair of conical members adapted to enter the bore of the roll and engage with the ends of the inner layers of paper.

5 The objection to this arrangement is that, owing to the small area of contact between the conical members and the roll, the ends of the inner layers of paper are frayed and torn away to such an extent as to cause a substantial waste of the paper stock.

10

The object of my invention is to provide simple and effective means for securing engagement of the supporting means with the interior of the bore of the roll throughout a substantial area, thus preventing appreciable loss of stock by fraying.

20 In the accompanying drawing, which illustrates one form of my device, Figure 1 is a side view; Figure 2 is an enlarged longitudinal section through one of the chuck members; Figure 3 is a fragmentary view similar to Figure 2 but showing the parts in expanded position; and Figure 4 is a section taken on the line 4—4 of Figure 2, and Figure 5 is a section taken on the line 5—5 of Figure 2.

30 The numeral 5 indicates the supporting shaft journaled at its ends in suitable bearings (not shown). The shaft is provided with a key-way 6 and has mounted upon it, adjacent to each end, a pair of chuck members for engaging with the bore of the paper roll, such members being of the same construction.

The body of each chuck member consists of a sleeve 7 provided adjacent its outer end with external threads 8 and having a reduced inner end 9. Mounted on the reduced inner end of the sleeve are a fixed collar 10 and a sliding collar 11. The collar 10 may be secured in position by pins 22. Each of the collars are provided with a plurality of pockets having inclined inner ends 12. Seated in the pockets are expansion bars 13 having their ends beveled to correspond with the angle of the ends 12. These bars are held in their retracted position by elastic bands 14, preferably of rubber. Positioned between the outer end of the sliding collar 11 and the shoulder 15, formed between the main and reduced parts of the sleeve, is a washer 16, preferably of bronze or similar bearing metal. Carried on the washer is a flange 17 extending beyond the periphery of the threaded portion of the sleeve. This projecting flange

is engaged by the face of a nut 18 internally threaded to cooperate with the threads 8. Any suitable means is provided for rotating the nut 18, such as radial holes 19, for engagement with an operating bar. The numeral 20 indicates a key 5 carried by the sleeve and engaging with the key-way 6 in the shaft to prevent relative rotary movement between these parts but to permit longitudinal movement of the sleeve on the shaft. To lock the sleeve against longitudinal movement 10 after the desired adjustment has been made, it is provided with a set-screw 21. This set-screw is preferably arranged in alignment with the key 20 so as to cooperate with the bottom of the key-way and thus prevent burring of the shaft with 15 consequent binding of the sleeve thereon. The key 20, in addition to preventing rotation of the sleeve on the shaft, also engages with a way in the collar 11 to prevent its rotation on the sleeve.

In using my device one of the chuck members 20 is removed from the shaft and the shaft passed through the bore of the paper roll until the other chuck member enters the bore and the end of the roll is adjacent to but out of contact with the flange 17. The first named chuck member is now 25 replaced on the shaft and similarly positioned with respect to the roll. Both chuck members are now locked against longitudinal movement by means of the set-screws and the nuts 18 rotated to force the sliding collars 11 toward the fixed 30 collars 10, as shown in Figure 3. This forces the expansion bars 13 outwardly, causing them to engage effectively with the inner periphery of the bore and so firmly clamp the roll in position on the shaft without injury to the stock. 35

Having fully described my invention, what I claim as new and desire to secure by Letters Patent of the United States is:

1. In a device of the class described, the combination with a shaft having a key-way, of a sleeve 40 on said shaft having a key engaging said key-way, said sleeve having a main threaded portion and a reduced portion, a fixed collar on said reduced portion adjacent its inner end, a sliding collar on said reduced portion adjacent its outer end, each 45 of said collars being provided with pockets having inclined walls, expansion bars positioned in said pockets and having inclined ends cooperating with the inclined walls of said pockets, elastic means for holding said bars in retracted position, 50 a washer abutting the sliding collar and projecting radially beyond the threaded portion, a nut on the threaded portion for actuating said washer to move the sliding collar in the direction of the length of the shaft, and means for locking the 55

sleeve against longitudinal movement on the shaft.

2. In a device of the class described, the combination with a shaft having a key-way, of a sleeve on said shaft, a fixed collar on said sleeve, a sliding collar on said sleeve, each of said collars being provided with pockets having inclined walls, expansion bars positioned in said pockets and having inclined ends cooperating with the inclined walls of the pockets, a key carried by the sleeve, said key engaging with the way in the shaft to prevent rotation of the sleeve on the shaft and with the sliding collar to prevent rotation of the collar on the sleeve, and means for locking the sleeve against longitudinal movement of the shaft.
3. In a device of the class described, the combi-

nation with a shaft having a key-way, of a sleeve on said shaft having a key engaging said key-way, said sleeve having a threaded and a non-threaded portion, a fixed collar on said sleeve adjacent its inner end, a sliding collar on the non-threaded portion of said sleeve, each of said collars being provided with pockets having inclined walls, expansion bars positioned in said pockets and having inclined ends cooperating with the inclined walls of said pockets, elastic means for holding said bars in retracted position, a nut on the threaded portion of the sleeve to actuate the sliding collar, and means for locking the sleeve against longitudinal movement on the shaft.
